(57) **CLAIM**

The ornamental design for a strobe for camera, as shown and described.

DESCRIPTION

FIG. 1 is a front view of a strobe for camera, showing our new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines in the drawings depict portions of the strobe for camera that form no part of the claimed design.
